F. H. & A. R. W. BASSETT,
SUPPORTING BRACKET FOR WINDOW SHADES AND CURTAINS.
APPLICATION FILED MAY 12, 1917.

1,282,728.

Patented Oct. 29, 1918.

UNITED STATES PATENT OFFICE.

FENWICK H. BASSETT AND ANNA R. W. BASSETT, OF NORWOOD, PENNSYLVANIA.

SUPPORTING-BRACKET FOR WINDOW SHADES AND CURTAINS.

1,282,728.

Specification of Letters Patent. Patented Oct. 29, 1918.

Application filed May 12, 1917. Serial No. 168,271.

To all whom it may concern:

Be it known that we, FENWICK H. BASSETT and ANNA R. W. BASSETT, citizens of the United States, residing at Norwood, 5 county of Delaware, and State of Pennsylvania, have invented certain new and useful Improvements in Supporting-Brackets for Window Shades and Curtains, of which the following is a specification.

10 Our invention consists of improved supporting brackets for window shades and curtains. One object of our invention is to provide brackets which can be easily and quickly attached to the movable sashes of 15 windows and which will be capable of supporting roller shades and curtains, thus enabling the shades and curtains to be moved bodily with the window sashes.

Another object is to so construct our improved supporting brackets that they will permit sufficiently wide shades and curtains to be used so as to completely cover the width of the window.

20 A further object is to so design our improved brackets that shades and curtains can be quickly attached thereto or removed therefrom.

25 A still further object is to so construct our improved brackets that they will be of simple construction and can be manufactured and sold at a low cost.

30 These objects and other advantageous ends which will be described hereinafter, we attain in the following manner, reference being 35 had to the accompanying drawings in which—

Figure 1 is a front elevation of a portion of a window having our invention thereon.

Fig. 2 is a horizontal cross section of Fig. 40 1 showing in outside view, the sashes, brackets, and elements which they support.

Fig. 3 is a fragmentary perspective showing one of our improved brackets secured to a movable sash and supporting a roller 45 shade and curtain pole.

Fig. 4 is a side view of one of our improved brackets.

Fig. 5 is a front view of the bracket shown in Fig. 4, and

50 Fig. 6 is a fragmentary side view showing one of our improved brackets having a hole therein for the cylindrical end of a roller shade.

Referring to the drawings, 1 represents 55 the window frame including a slidable upper sash 2 and a slidable lower sash 3. These

sash, as is usually the custom, slide between strips 4 secured to the oppositely disposed inner surfaces of the window frame.

A pair of our improved brackets 5 and 6 are secured to the upper portion of the sash 2. The brackets 5 and 6 are substantially the same general construction with the exception of a slight change in detail for supporting the opposite ends of a shade roller. 65

The bracket 5 is preferably made of pressed metal and includes a plate 5^a which is preferably turned at right angles to an arm 7. The plate 5^a is provided with screw holes and is adapted to be secured to the 70 movable sash by means of screws 8. The arm 7 has an off-set portion 9 which is sufficiently far removed from the plate 5^a to extend in front of the window frame 1 as clearly shown in Fig. 2. 75

The off-set portion 9 as illustrated, is made substantially at right angles to the portion 10 of the arm 7 and has a forwardly projecting portion 11. This projecting portion 11 has a notch 12 to receive the angular 80 end 13 of a shade roller 14 (see Fig. 4).

The projecting portion 11, at its outermost end, has a finger 15 designed to project through an opening 16 in a curtain pole 17. A recess 18 is formed in the upper edge of 85 the projecting portion 11 and forms a receptacle for receiving one end of the curtain pole if the latter is not provided with a hole similar to 16. In other words, the curtain pole can be supported either on the finger 15 90 or within the recess 18 considering that the bracket 6 also has a finger 15 and recess 18 to support the opposite end of the curtain pole. The bracket 6, as above noted, is substantially identical with the bracket 5 with 95 the exception that instead of having the notch 12, a hole 19 is provided (see Fig. 6).

Furthermore, the portion 9 of the bracket 6 extends in an opposite direction to that in which the portion 9 of the bracket 5 extends in order to permit the end of the shade roller 14 which has the cylindrical portion 20 thereon to extend beyond the opening in the window frame as clearly shown in Fig. 2, it being noted that the 100 cylindrical portion 20 of the shade roller fits and is free to rotate within the hole 19 in the bracket 6.

We preferably secure the brackets 5 and 6 adjacent the top portion of the upper sash 110 2 and the portions 10 of the brackets are sufficiently long to extend to the inside of the

room in which the window is located. By this construction and arrangement, it is possible to lower the window from the top to secure air in the room without interfering 5 with the curtain or shade, since the curtain and shade will be lowered with the window sash. Thus, our invention is of practical use and is extremely efficient.

While we have described our invention as 10 taking a particular form, it will be understood that the various parts of our invention may be changed without departing from the spirit thereof, and hence we do not limit ourselves to the precise construction 15 set forth, but consider that we are at liberty to make such changes and alterations as fairly come within the scope of the appended claim.

Having thus described our invention, what 20 we claim as new and desire to secure by Letters Patent is:

A pair of brackets, each of said brackets having an integral portion designed to be secured to the movable sash of a window; an arm projecting downwardly from said first portion; an integral offset portion on said arm of sufficient distance from said first portion to extend in front of the window frame; and a projecting portion leading from said offset portion, said latter projecting portion having a part adapted to support a curtain pole and another part adapted to support the ends of a shade roller, substantially as described.

In testimony whereof we have signed our 35 names to this specification in the presence of two subscribing witnesses.

FENWICK H. BASSETT.
ANNA R. W. BASSETT.
